UNITED STATES PATENT OFFICE.

RICHARD KITSON, OF LOWELL, MASSACHUSETTS, ASSIGNOR TO THE KITSON MACHINE COMPANY, OF SAME PLACE.

MACHINE FOR OPENING COTTON.

SPECIFICATION forming part of Letters Patent No. 406,050, dated July 2, 1889.

Application filed September 11, 1883. Serial No. 106,214. (No model.)

To all whom it may concern:

Be it known that I, RICHARD KITSON, of Lowell, in the county of Middlesex and State of Massachusetts, have invented a new and useful Improvement in Machines for Opening Cotton, of which the following is a specification.

My improvement relates to that class of mechanisms for opening and cleaning cotton known as "cotton-trunks;" and it consists in providing said cotton-trunks with a mechanism for automatically conveying away the dirt and leaf from the dirt-chambers, where it is deposited by the action of the trunk in cleaning the cotton, substantially as hereinafter described and claimed.

In the drawings, Figure 1 shows a sectional view of a cotton-opener and part of its trunk with the present improvements applied to the trunk and with part of the picker broken away. Fig. 2 is a side elevation of the same.

B is an ordinary cotton-opener beater. b b are feed-rolls, and c is a portion of a feeding-apron, the same being shown in dotted lines. C is a fan for producing a current of air, which takes the comminuted cotton from the beater after the latter and the feed-rolls have picked the same, and carries it through the trunk D, intermingled with the air-current, to remove the dirt, leaf, &c. All these parts, except the attachments of the trunk, hereinafter described, are constructed and combined together in the ordinary way, and operated in the usual and well-known manner, so that further description of them is unnecessary.

After the current of air and commingled cotton fiber has entered the trunk and reached its horizontal part, it passes over the wire screen or slat bottom d of this part of it, and the dirt, leaf, and impurities, which are heavier than the floating fiber, drop downward and separate from the latter, dropping through the screen or slat bottom, while the fiber is carried onward. Below the screen-bottom d are placed the vertical transverse partitions d', forming chambers in connection with the sides of the trunk and screen-bottom for the reception of the falling dirt and impurities. These chambers prevent the latter from being sucked or drawn back and upward again

through the bottom d, and insure their final separation from the fiber.

Below the chambers formed between the partitions d', I construct my apparatus for carrying away the dirt which falls into them, as follows: The vertical longitudinal sides of the trunk, which sustain the partitions d' at each end, are carried downward below their lower edges, and the bottom E is secured to them so as to form a longitudinal passage, into which the bottoms of the chambers between the partitions d' open, and which extends beyond said chambers and terminates in a dust-chamber F, extending downward, as shown. At the ends of bottom E, which is flat upon its upper internal surface, are mounted rollers e e, extending across the same, around which are passed endless cords e⁵, as shown, to which are attached a series of scrapers e' e' at suitable intervals. These scrapers are formed of slats of wood or other material of the proper shape and length to fit closely at their bottom edges and ends to the bottom E and sides of the trunk, and prevent the passage of the dirt or air beneath them as they are drawn along by the cords e⁵, which is accomplished by one of the rollers e being revolved in the proper direction by the pulley e⁶, attached to its prolonged axis on the outside of the trunk, and a belt e⁷, as hereinafter described. The scrapers e' e', when thus drawn along over the bottom E, continually carry the dirt and impurities which have fallen upon the bottom ahead of them and drop or deposit it in the chamber F. A roller e² is placed over the driven roller e to allow the dirt to escape under it, while preventing the escape of air past it to a great extent. This is accomplished by mounting the ends of the axis of roller e², which project beyond it, in vertical slots e⁸ in the side walls of the trunk, of such a breadth as to allow the axis to move up and down in them without horizontal play. The roller e² can therefore rise when the scrapers e' e' or masses of dirt pass beneath it, and drop back again after they have passed, thus preventing the escape of air beneath it or past its ends in a great measure.

A box or receptacle G may be placed in the chamber F to receive the dirt and impurities

deposited in it, if desired; or the dirt may be removed by other means if the box G is omitted. For this purpose a door b' is made in the side of the chamber, Fig. 2, which is suspended upon hinges b² b³, at its upper end.

The various revolving parts of the mechanism described may be driven from counter-shafts or pulleys in various ways; but I have shown in Fig. 2 a method by which they may be driven. A belt a drives pulley a' upon the end of the prolonged beater-shaft. From pulley a² on the same shaft a belt drives pulley a⁴ on the shaft of the upper feed-roll b. From pulley a⁵ on the beater-shaft a belt drives pulley a⁶ on the shaft of fan C. From pulley a⁶ upon the latter shaft a belt drives pulley a⁷ upon the end of the shaft of a roller of feed-apron c. From pulley a⁸, upon the latter shaft, the belt e⁹ drives pulley e⁸ of roller e, before described.

The advantage of providing a longitudinal passage in connection with the chambers between the partitions d' d', extending to a space or chamber beyond them, together with a suitable mechanism for removing the dust and impurities therefrom which are deposited therein from said chambers, is that said chambers and passage may be cleaned out when the cotton opener and trunk are in operation without affecting the same. This obviates the expense of stopping the entire machine to clean out the compartments of the trunk under screen-bottom d during working-hours in the mill, or of doing it in extra time of the workmen afterward, and causes the cotton-trunk to be kept at the highest state of efficiency by having its compartments beneath screen-bottom d kept constantly in a comparatively clean state.

If it is desired to operate the scrapers e' e' intermittently, the belt e⁹ may be thrown on and off pulley e⁸, as required.

The combination of the longitudinal passage connecting with the chambers between the partitions d' d' and opening into the dust space or chamber F, the fiber-passage and screen-bottom d of the trunk being located above said partitions, are the features of the construction which render the employment of a unitary means or mechanism feasible—such as the connected scrapers e'—to keep the chambers between those partitions clean while the trunk is in operation, because it would not be practically possible without these features to employ a simple and convenient mechanism in the cleaning, which must necessarily operate upon the contents of each of the chambers between the partitions d' d' separately from that of the others.

The dust-chamber F performs the function, in connection with the dust-passage, which conveys the dust and impurities from beneath the screen-bottom d, of keeping the dust and impurities discharged from the chambers or spaces between the partitions d' d' confined, and preventing their lodging upon the cotton which is being fed to the beater B over apron

c and from being sucked into the space around the beater through the openings by which it is surrounded and intermingling with fresh masses of cotton as they are fed through the opener to the trunk. This function of the dust passage and chamber F is performed by them both while said scrapers are in operation and thrown out of operation, as described, as they prevent currents of air taking up the dust as it falls from the chambers between partitions d' d' and carrying it to the beater.

As the scrapers e' e' consist of transverse slats inclosing spaces between them open at the top and lying closely upon the bottom E, they thus of themselves form shallow chambers or boxes, which prevent the dust and impurities from being drawn out of them by eddies or counter-currents of air after being deposited therein and until discharged by the progressive movement of the scrapers into the dust-chamber F.

What I claim as new and of my invention is—

1. The combination of the beater B, the trunk D, containing the horizontal air and fiber passage, the screen-bottom d beneath the same, and the transverse partitions d' d', which form with the trunk and screen-bottom d chambers beneath the latter, the dust-passage running longitudinally along said trunk beneath said screen-bottom, connected to said chambers and adapted to receive the dust and impurities discharged therefrom and conduct the same to the dust-chamber F, and the latter adapted to receive the dust and impurities discharged into it from said dust-passage and prevent them from reaching fresh fiber while being fed past the beater, substantially as described.

2. The combination of the feed-apron c, feed-rolls b b, the beater B, the trunk D, containing the horizontal air and fiber passage, screen-bottom d beneath the same, and transverse partitions d' d', which form with the trunk and screen-bottom d chambers beneath the latter, and the dust-passage running longitudinally along said trunk beneath said screen-bottom and connected to said chambers and adapted to receive the dust and impurities discharged therefrom and to conduct the same to the dust-chamber F, and the latter adapted to receive the dust and impurities discharged into it from said dust-passage and prevent them from reaching fresh fiber while being fed over said feed-apron and past said beater, substantially as described.

3. The combination of the beater B, the trunk D, containing the horizontal air and fiber passage, the screen-bottom d, and the transverse partitions d' d', which form with the trunk and screen-bottom d chambers beneath the latter, the dust-passage running longitudinally along said trunk beneath said screen-bottom, connected to said chambers and adapted to receive the dust and impurities discharged therefrom and to conduct the

same to the dust-chamber F, and means whereby said dust and impurities may be conveyed to said dust-chamber F through and out of said dust-tube, with the chamber 5 adapted to receive said dust and impurities discharged into it from said dust-passage and prevent them from reaching the fiber being fed past the beater, substantially as described.

4. In a cotton-trunk, the combination of the 10 air and fiber passage, the screen-bottom d beneath the same, the partitions d' d', forming with the trunk and screen-bottom chambers below the latter, the dust-passage below said chambers running longitudinally along said 15 trunk beneath said screen-bottom and connected with said chambers and adapted to receive the dust and impurities discharged therefrom, and one or more scrapers e', adapted to traverse said dust-passage and clear 20 out the same, with mechanism for operating said scrapers, substantially as described.

5. In a cotton-trunk, the combination of the air and fiber passage, the screen-bottom b beneath the same, the partitions d' d', forming with the trunk and screen-bottom chambers 25 below the latter, the dust-passage below said chambers running longitudinally along said trunk beneath said screen-bottom and connected with said chambers and adapted to receive the dust and impurities discharged 30 therefrom, the dust-chamber F, connected to said dust-passage, and one or more scrapers e', adapted to traverse said dust-passage and move its contents forward to said dust-chamber, with mechanism for operating said 35 scrapers, substantially as described.
